UNITED STATES PATENT OFFICE

2,421,833

TURBINE CONSTRUCTION

Val Cronstedt, Marlboro, and Walter A. Ledwith,
Hartford, Conn., assignors to United Aircraft
Corporation, East Hartford, Conn., a corpora-
tion of Delaware

Application May 11, 1943, Serial No. 486,619

9 Claims. (Cl. 253—69)

1

This invention relates to a gas turbine particularly adapted for use in aircraft.

In earlier turbines, particularly of the multi-stage type, the casing has been made in opposed sections separable along lines parallel to the axis of the turbine shaft. These lines of separation are difficult to seal because of the distortion of the sections as they become heated by the driving fluid. Moreover, the elements within the casing, such as the rows of nozzles and the seals at the outer ends of the blade rings and at the inner edges of the rows of nozzles, must be mounted within the casing sections before they are put together.

One object of this invention is to overcome these difficulties by building the casing in a series of rings in end-to-end engagement with a single row of nozzle-forming guides on each ring.

In assembling a casing made up of a series of rings, it may be advantageous to have some of the rings split, and a feature of this invention is the positioning of the split rings so that the planes of the splits are out of alignment. This arrangement makes a stronger casing, free from a single line of separation extending the entire length of the casing.

The conventional turbine casing built up in opposed sections has split sealing rings mounted in line with the rows of blades on the rotor to reduce the leakage around the outer ends of the blades. A feature of this invention is the mounting of these seals in the form of rings positioned between adjoining casing rings.

Another feature of the invention is the mounting of a casing, built up of a series of rings, by supports all of which engage a single ring. The invention also involves mounting of the inlet scroll on the casing ring engaged by the supports so that loads on the scroll will be transmitted directly to the supports.

Other objects and advantages will be apparent from the specification and claims, and from the accompanying drawings which illustrate what is now considered to be a preferred embodiment of the invention.

Fig. 1 is a sectional view through the turbine.

Fig. 2 is a sectional view of the turbine casing substantially on the line 2—2 of Fig. 1.

The turbine, as shown, includes a casing 4 and a rotor 6 both supported in a housing 8. The casing is supported by radially extending pins 10 carried by the housing and engaging bores in bosses 12 in the casing. These pins are all in substantially the same plane and constitute the sole support for the casing. The casing is thus

2

free to expand lengthwise within the housing. The casing, in the plane of the pins, is smaller than the housing, and clearance 13 is provided at the inner ends of pins 10 to permit the casing to expand radially.

Housing 8 has a head 14 which forms a part of the housing and supports a bearing sleeve 16 for the front end of the turbine shaft 18 integral with rotor 6. At the other end of the turbine 10 rotor, housing 8 has a spider 20 within which is a bearing 22 for the turbine shaft. The spider has a plurality of legs 24 engaging radially positioned pins 26 carried by the housing.

The casing is built up of several rings 28, 30, 15 32 and 34, each of which has a single row of nozzle-forming guides 36. These rows of guides alternate with cooperating rows of blades 38 on the turbine rotor. Bosses 12 are located in casing ring 30 so that all the supporting pins 10 engage 20 ring 30.

An intake scroll 40 which directs the driving fluid to the row of nozzles on the first casing ring 28 has an integral flange 42 by which the scroll may be mounted on ring 30, which receives the supporting pins so that any loads on the scroll are transmitted directly to ring 30 and thence to the housing.

Casing rings 30, 32 and 34 are split on longitudinal planes and each plane of separation 44, 46 30 and 48 of the adjoining rings is angularly spaced or staggered with reference to the other planes. The split parts of said ring are held together by clamping bolts 50. When the rings are held together in end-to-end relation by clamping bolts 35 51, the tendency of any one of the split rings to separate is prevented by the adjoining casing rings.

Sealing rings 52, which control the leakage of driving fluid around the outer ends of the rows 40 of blades on the rotor, may be positioned between adjoining casing rings. As shown, each sealing ring has a flange extending between adjoining casing rings, and held by the same clamping bolts that hold the casing rings together. Each ring, 45 which may be continuous, has one or more inwardly extending sealing fins 56, the edges of which are close to the periphery of the rows of blades. The sealing rings have laterally extending surfaces 57 which engage surfaces of the casing rings for aligning the adjoining rings.

The end casing ring 34 which extends beyond the center line of the last row of blades on the rotor may have its sealing rings 58 mounted in grooves within the ring. The outer end of this 55 casing ring may carry large diameter expansible

seals 60 which engage the end of the exhaust duct 62.

It is to be understood that the invention is not limited to the specific embodiment herein illustrated and described, but may be used in other ways without departure from its spirit as defined by the following claims.

We claim:

1. In a turbine construction, a housing, a casing within the housing comprising a plurality of rings in end-to-end engagement, at least some of said rings being split longitudinally, and supporting means for the casing extending between the housing and one of said rings, said supporting means constituting the sole support for the casing.

2. In a turbine construction, a housing, a casing within the housing comprising a plurality of rings in end-to-end engagement, at least some of said rings being split longitudinally with the lines of separation of adjoining rings angularly spaced from each other, and supporting means for the casing extending between the housing and one of said rings between the end rings.

3. In a turbine construction, a housing, a casing within the housing, and comprising a plurality of rings, each of which has a row of nozzle-forming guides thereon, and means between the housing and casing and engaging with one only of the casing rings between the end rings for supporting the casing within the housing.

4. In a turbine construction, a casing comprising several rings in end to end engagement, supporting means for the casing engaging one of said rings, and an intake scroll for the turbine mounted on the ring with which the supporting means engage.

5. In a turbine construction, a casing comprising several rings in end to end engagement, supporting means for the casing engaging one of the rings between the end rings, and an intake scroll for directing fluid to an end ring, said scroll being connected directly to the ring with which the supporting means engage.

6. In a turbine, a casing comprising several rings in end to end engagement, each ring having a row of nozzle-forming guides thereon, a rotor having rows of blades cooperating with the rows of guides on the casing, and labyrinth seals mounted between adjoining casing rings in alignment with the rows of blades on the turbine, and means for holding adjoining rings together and for clamping the seal in place.

7. In a turbine construction, a housing, a casing within said housing comprising several rings mounted in end to end engagement, each ring having a row of nozzle-forming guides thereon, a plurality of radially extending pins carried by the housing and engaging with one of said rings and constituting the sole support for said casing within the housing, and means for holding the rings together.

10 8. In a turbine construction, a housing, a casing within said housing comprising several rings mounted in end to end engagement, each ring having a row of nozzle-forming guides thereon, a plurality of radially extending pins carried by the housing and engaging with one of said rings and constituting the sole support for said casing within the housing, and an intake scroll connected directly to the ring with which the radially extending pins engage.

20 9. In a turbine, a casing comprising several rings in end to end engagement, each ring having a row of nozzle-forming guides thereon, a rotor having rows of blades cooperating with the rows of guides on the casing, and labyrinth seals mounted between adjoining casing rings, each seal having laterally projecting substantially cylindrical concentric surfaces on opposite sides thereof engageable with cooperating substantially cylindrical surfaces on the adjoining rings for aligning said rings with each other.
